I. B. JOHNSON.

UNDERWAIST.

APPLICATION FILED JAN. 2, 1917.

1,235,481.

Patented July 31, 1917.

Inventor

IDA B. JOHNSON

By *Watson E. Coleman*
Attorney

UNITED STATES PATENT OFFICE.

IDA BASSETT JOHNSON, OF CROSBYTON, TEXAS.

UNDERWAIST.

1,235,481.

Specification of Letters Patent. Patented July 31, 1917.

Application filed January 2, 1917. Serial No. 140,189.

To all whom it may concern:

Be it known that I, IDA BASSETT JOHNSON, a citizen of the United States, residing at Crosbyton, in the county of Crosby and 5 State of Texas, have invented certain new and useful Improvements in Underwaists, of which the following is a specification, reference being had to the accompanying drawings.

10 This invention relates to underwaists and more particularly to a waist of this character particularly designed for juveniles, the primary object of the invention being to provide stocking supports which are so connected and secured to the waist body that a lateral pull upon the shoulder straps of the waist is eliminated and said straps retained in their proper positions upon the shoulders.

15 It is another and more particular object of the invention to provide a child's waist or similar garment having separable fastening means at the back, and straps extending obliquely in intersecting relation across the front of the garment, each of said straps 20 having a free end portion adapted to be extended across the back of the garment and detachably connected to the other end of the strap, and stocking clasps on each of the 25 free end portions of said straps adapted to 30 be connected to the outer sides of the stockings.

It is a further general object of my invention to provide an article of the above character which is exceedingly simple, may be 35 produced at small cost, and is comfortable in use as well as serviceable and efficient for the purpose in view.

With the above and other objects in view, my invention consists in the novel features 40 of construction, combination and arrangement of parts to be hereinafter more fully described, claimed and illustrated in the accompanying drawing, in which,

45 Figure 1 is a rear elevation showing the garment applied;

Fig. 2 is a front perspective view; and

Fig. 3 is an enlarged fragmentary elevation of the rear side of the garment.

Referring in detail to the drawing, 5 designates the body of the waist which may be 50 constructed of linen, muslin, wool, or any other desired material. This waist body includes the shoulder straps 6 and the rear side of said body is open, the opposite edges 55 thereof being brought together and connected by buttons or other suitable detach-

able fasteners, indicated at 7. The lower edge of the garment body is reinforced by a band 8, to which spaced pairs of buttons 9 are attached for a purpose which will be 60 obvious.

Straps 10 extend across the front wall of the garment body on the exterior thereof, in intersecting relation, and are securely stitched to said body wall. These straps 65 are extended over and secured to the shoulder portions of the waist, being disposed in intersecting relation as indicated at 11. The terminals of the straps are free and extend beyond the opposed edges of the back 70 portions of the garment and are adapted to be disposed in overlapping, intersecting relation as seen in Fig. 3 of the drawing. These intersecting terminal portions of the straps are provided with spaced buttons 12. 75 The other end portions of the straps 10 hang below the lower edge of the garment body and are extended upwardly at the back of the garment and securely stitched to the band 8, the ends 13 being free to extend 80 above said band, as indicated at 13'. The terminals of these latter portions 13 of the straps are provided with button holes and are disposed in intersecting relation, as clearly shown in Fig. 1, to be connected to 85 the buttons 12 on the other terminals of the straps. To the hanging portions of the straps 10 which extend below the lower edge of the garment, suitable clasps or fasteners 14 are attached, to be connected to the upper 90 edges of the stockings, as shown in Fig. 2. After the strap terminals have been connected in the manner described, the garment is fastened or closed down the back upon the body of the child. 95

From the foregoing description, taken in connection with the accompanying drawing, the construction and manner of use of the device will be clearly and fully understood. The waist may be very easily and quickly 100 applied and fastened upon the body, and the downward pull upon the straps 10 being in relatively opposite, oblique lines by the connection of the clasps or fasteners 14 to the outer sides of the stockings at their upper 105 edges, the shoulder portions 6 of the garment body will not be pulled off of the shoulders but will be tightly held in place thereon. The garment can, of course, be made in various sizes and any desired form of stocking clasp or fastener may be employed in 110 connection with the device. It is also to be

understood that while I have illustrated the preferred form, construction and arrangement of the retaining straps for the waist or garment, the same are susceptible of considerable modification therein and I, therefore, reserve the privilege of adopting all such legitimate changes as may be fairly embodied within the spirit and scope of the invention as claimed.

10 Having thus fully described my invention, what I desire to claim and secure by Letters Patent is:—

15 1. A waist having a separable back portion and fastening means therefor, straps extending obliquely in intersecting relation across the front wall of the waist body and permanently secured thereto, said straps also extending over the shoulder portions of the waist and being stitched to the back portions 20 of the waist, the terminals of the latter portions of the straps being provided with fastening elements, the other end portions of said straps extending below the lower edge of the garment body and then upwardly and permanently stitched to the separable back portions of the garment, the terminals of the latter portions of the straps

being free and provided with means for connection to said fastening elements, and stocking clasps on the portions of the straps 30 which depend below the garment body.

2. A waist including a body having a separable back portion and fastening means therefor, obliquely disposed, intersecting straps extending over the front wall of the garment, the shoulder portions and the back wall thereof permanently stitched thereto, the terminals of the latter portions of said straps intersecting at the separable edges of the back of the garment and each being provided with fastening elements, the other end portions of the straps extending below the garment and being extended upwardly and stitched to the back sections of the garment, the terminals of the latter end portions of 45 the straps being provided with means for detachable connection to said fastening elements, and stocking clasps on the free portions of the straps extending below the body 50 of the garment.

In testimony whereof I hereunto affix my signature.

MRS. IDA BASSETT JOHNSON.
